UNITED STATES PATENT OFFICE

THOMAS M. KEEFE, OF BOSTON, MASSACHUSETTS, ASSIGNOR TO J. P. EUSTIS MANUFACTURING COMPANY, OF CAMBRIDGE, MASSACHUSETTS, A CORPORATION OF MASSACHUSETTS

SHELF BRACKET

Application filed January 19, 1932. Serial No. 587,460.

This invention relates to brackets for supporting shelves or other articles which the brackets are adapted to hold, and such bracket comprises a very simple combination of a relatively few essential parts, for gripping or clamping a shelf or other article rigidly in the desired position. The preferred construction of the improved bracket presents a number of objects and advantages, but all of these may not necessarily be resorted to.

By preference the specific objects and advantages incident to the specifically illustrated and described bracket are as follows: 15 The parts of the bracket coordinate in a positive manner to grip or hold a shelf, and such bracket is therefore not dependent upon spring tension in connection with any part thereof. One of the objects is to provide an end piece for clamping or gripping the front edge of a shelf, such end piece being adjustable to a fixed position so that it will not vibrate and become loose. The assembly of such specific bracket consists of 20 three pieces only, a main part or bracket proper which fastens to the wall, an adjustable member and a nut for adjusting such member, all constructed and assembled in such way that no parts will weaken or 25 break. Also, the grip of the movable end piece is positive upon the shelf, with a tendency to lock the adjusting nut when the nut is set.

Further objects of the invention may be, 30 and preferably are, to so construct the bracket that it is adapted to clamp rigidly in position shelves with either flat or rounded edges, and it is not necessary to use shelves with specially beveled edges, these being 35 liable to chip and fracture quite easily; and also to provide a simple construction which lends itself to economy in production and to artistic or ornate lines.

With specific objects such as these in view, 40 the invention specifically consists of certain

features of construction and combinations of parts such as hereinafter described and then claimed with reference to the accompanying drawing illustrating one embodiment of the invention, and wherein

50

Fig. 1 is a side elevation of the improved bracket with a cross-section of a shelf, the end piece being shown as moved to an outward position so as to permit the shelf to be rested upon the bracket;

55

Fig. 2 is a sectional view, partly in elevation, of the bracket, a shelf being shown as rigidly held by the bracket;

60

Fig. 3 is a top plan of the bracket, the end piece being shown in the position illustrated in Fig. 1; and

Fig. 4 is a cross-section of the bracket on the line 4—4, Fig. 3, as viewed in the direction of the arrows.

Preferably all parts of the bracket are 65 made of metal. The bracket proper 10 is adapted to support a glass shelf 11 or other article, for use in the bathroom or wherever the occasion may demand. The base 12 of the bracket which is to set flat against the 70 wall may be secured to the wall in any desired manner, or by means of an attaching device 13 secured to the wall and to which the bracket proper 10 is rigidly attached by means of a set-screw 14, following if desired 75 the invention forming the subject matter of a separate application.

From the base 12 out to the extreme outer terminal of the bracket its top surface 15 is formed flat, so that the shelf 11 may properly rest upon the bracket. Just beyond the outer terminal of the bracket proper 10, and which terminal is preferably squared off at right angles to the longitudinal axis of the bracket proper, there is located a movable end piece or finger 16 serving as gripping means to positively abut the front edge of the shelf. This end piece extends upwardly and is formed with an inner portion 17 which is squared off at its inner face so as to cor- 80 85 90

respond with the squared off terminal of the bracket proper.

Movable end piece 16 is rigidly fixed to or formed integrally with the outer end of 5 a cylindrical stem 18 which stem has a reduced extension 19. Such stem is inserted into a longitudinal bore or hole 20 in the bracket proper. Preferably this bore is about one-half the length of the bracket 10 proper, it being extended inwardly to form a reduced portion 21.

The larger portion 18 of the stem is of 15 cylindrical shape and smooth so as to fit slidingly into the correspondingly shaped bore 20, which is also smooth. The reduced extension 19 of the stem is spaced slightly away from the surface of the reduced portion 21 of the bore, preferably so as to avoid frictional engagement with such surface.

20 Intermediately of the length of the bore, the bracket proper is formed with an intersecting aperture 22 which opens out at both sides of the bracket. An adjusting nut 23 with a knurled edge is arranged in the aperture 22, its thread engaging with a screw-threaded length 24 of the stem.

It will be seen that the opposite sides of 30 the nut project slightly from the bracket proper so that the same may be rotated by the fingers. When the nut is rotated in one direction, the end piece 16 is moved in a direction away from the outer terminal of the bracket proper, so that a shelf or article such as the shelf 11 may be rested upon the 35 flat upper surface of the bracket proper, as shown in Fig. 1. When the shelf is in such position it may now be rigidly clamped in such position by turning the nut 23 in the opposite direction, thereby advancing the 40 end piece 16 into firm abutting and positive abutting contact with the front edge of the shelf, assuming that the shelf abuts the base member 12 at its rear edge. The setting home of the nut 23 during such fixation will 45 cause the nut at its front face to bear firmly upon the front face of the aperture 22, thereby acting to rigidly lock the nut, and hence the parts operated thereby in the final position. Such adjustments are permitted by 50 the simple telescopic connection of the end piece 16 with the bracket proper 10.

Inasmuch as the adjusting nut is free 55 from frictional engagement with the front wall of the aperture 22 when the end piece is removed outwardly from clamping position on the front edge of the shelf, it is desirable that simple means be provided for maintaining the end piece 16 so as to point upwardly, thus requiring only the use of one hand in turning the nut 23 and adjusting the end piece outwardly and inwardly. Such positioning means is associated with the bracket at a point between the stem 18 and the outer end of the gripping piece 16 and 60 consists in a telescopic connection between 65

the inner portion 17 of the end piece and the adjacent terminal of the bracket proper. Such associated means preferably resides in a hole 25 which is formed in the bracket terminal, in between the flat upper surface 15 of the bracket and the bore 20, together with a pin 26 which extends inwardly from the inner face of the portion 17 and is guided in the said hole 25. The two telescopic connections between the end piece and the bracket proper are parallel. Preferably the length of the positioning pin 26 is more or less determined relatively to the length of the portion 21 of the bore in the bracket, which extends to the rear of the aperture 22. 70 Therefore, the length of the pin 26 is made less than the length of the rear portion of the stem which is intersected by the nut 23, when the parts are in gripping position. Therefore, it will be seen that when the end piece 16 is adjusted to the position shown in Fig. 1, or even to such position as to disengage the pin 26 from its hole, there will be a short portion of the stem extending rearwardly into the hole back of the aperture 22. 80 In actual practice with given proportions between the shelf and the length of the bracket, the end piece will always be positioned in a direction to extend upwardly, assuming that a range of adjustment is desired such as to care for slight variations which may be encountered in shelves which are supposed to be of the same widths. 85

In practice it is preferred that the base 12 of the bracket act as the seat member 100 against which the inner edge of a shelf may be clamped, and in such case it is preferred that the forward face of the base be provided with a hump 27 having an inclined underface 28 to facilitate positioning the rear edge of the shelf, and to act as a stop against the upward movement of the shelf when it is positively clamped in position. Therefore, to release the shelf it is essential to positively move the end piece 16 away from it, by means of the adjusting nut 23. It will furthermore be seen that any pressure upwardly against the shelf will not release it, because the positive grip must first be overcome. 110

Obviously, the invention is susceptible to more or less modification without departing from the spirit of the invention as defined in the scope of the appended claims.

What I claim as new is—

1. A supporting bracket, including the combination of a bracket proper having means for fixing it in supporting position, and having a rest surface, a movable end-piece angularly projecting therefrom beyond the rest surface for bearing at its inner edge on an article supported on the rest surface, means for positively adjusting the end-piece for such purpose, and means directly associated with the outer extremity of the brack- 125 130

et proper and the projecting inner edge of the end-piece for maintaining the end-piece so as to extend in a given direction with respect to the bracket proper.

- 5 2. A supporting bracket, including the combination of a bracket proper having means for fixing it in supporting position, and having a rest surface, a movable end-piece angularly projecting therefrom beyond the rest surface for bearing at its inner edge on an article supported on the rest surface, means for positively adjusting the end-piece for such purpose, and means directly associated with the outer extremity of 70
10 the bracket proper and the projecting inner edge of the end-piece for maintaining the end-piece so as to extend in a given direction with respect to the bracket proper, such associated means comprising a telescopic 75
15 connection located between the respective ends of the projecting end-piece.

3. A supporting bracket, including the combination of a bracket proper having means for fixing it in supporting position, 80
25 and having a rest surface, a movable end-piece angularly projecting therefrom beyond the rest surface, for bearing at its inner edge on an article supported on the rest surface, means for positively adjusting the 85
30 end-piece for such purpose, the bracket proper having a hole in its outer extremity and the end-piece having a pin extending inwardly from its projecting inner edge and guided in the hole, for maintaining the end-piece so as to extend in a given direction with respect 90
35 to the bracket proper.

4. A supporting bracket, including the combination of a bracket proper, provided with a bore extending through its outer end, 95
40 a stem guided longitudinally in the bore and screw-threaded on its inner end, the bracket proper having lengthwise thereof a rest surface for an article, and having a side aperture extending from the bore at a point below the rest surface and opposite the screw-thread, such aperture being located between the ends of such rest surface, a rotatable nut positioned in the aperture and threaded onto such screw-thread, and an end-piece located outside of the bracket proper and projecting at an angle to the outer end of the stem, for positive engagement with the article supported on the rest surface of the bracket proper.

5. A supporting bracket, including the combination of a bracket proper having an angularly projecting seat member at its inner end and provided with a smooth bore extending through its outer end, a stem guided longitudinally in the bore and screw-threaded on its inner end, the bracket proper having lengthwise thereof a rest surface for an article, and having a side aperture extending from the bore at a point below the rest surface and opposite the screw- 100
50

thread, such aperture being located between such seat member and the outer end of the bracket, a rotatable nut positioned in the aperture and threaded onto such screw-thread, and an end-piece located outside of the bracket proper and projecting at an angle to the outer end of the stem, whereby turning of the nut acts to cause the end-piece to positively clamp an article between the end-piece and seat member. 105
75

6. A supporting bracket, including the combination of a bracket proper, provided with a smooth bore extending through its outer end, a stem guided longitudinally in the bore and screw-threaded on its inner end, the bracket proper having a side aperture extending from the bore at a point opposite the screw-thread, a rotatable nut positioned in the aperture and threaded onto such screw-thread, and an end-piece located outside of the bracket proper and projecting at an angle to the outer end of the stem, for positive engagement with an article supported by the bracket proper, and means directly associated with the bracket proper and the end-piece and located between the stem and the outer surface of the bracket proper, for maintaining the end-piece so as to extend in a given direction with respect to the bracket proper. 110
80
90
95

7. A supporting bracket, including the combination of a bracket proper having an angularly projecting seat member at its inner end, and provided with a smooth cylindrical bore extending through its outer end and an aperture extending transversely through the bracket proper and intersecting the bore intermediately of its length to divide the bore into a rear portion and a forward portion, the bracket proper also having a rest surface for an article and extending over the bore, a cylindrical stem in one piece having a smooth portion guided in the forward portion of the bore and having a screw-threaded inner portion entering the rear portion of the bore, a rotatable nut disposed in the aperture at a point below such rest surface and threaded onto the screw-thread, and an end-piece rigidly mounted on the outer end of the stem and projecting at an angle thereto, whereby the turning of the nut acts to clamp an article between the end-piece and seat member and to frictionally bind the nut against the forward wall of the aperture. 115
100
105
110

8. A supporting bracket, including the combination of a bracket proper having a projecting seat member at its inner attachment end and provided with a bore extending through its opposite end, a stem guided longitudinally in and concealed in the bore, and screw threaded on its inner end, the bracket proper having a rest surface for an article and a side aperture extending from the bore at a point opposite the screw thread, 120
125
130

such aperture being located between such seat member and the outer end of the bracket, a rotatable nut positioned in the aperture and threaded onto such screw thread, the nut slightly protruding laterally of the bracket and below such rest surface, and an end-piece located outside of the bracket proper and projecting at an angle from the outer end of the stem, whereby the turning of the nut below the article acts to cause the end piece to positively clamp the article between the end piece and seat member.
